UNITED STATES PATENT OFFICE.

JOAQUIN S. ABREU, OF SAN FRANCISCO, CALIFORNIA.

AEROPLANE.

Application filed February 11, 1926. Serial No. 87,591.

My invention relates to improvements in aeroplanes wherein a fuselage, provided with planes and a rudder, and controlling means therefor, is arranged to be releasably secured 5 upon a body, provided with propelling mechanism to permit said fuselage to be released and entirely separated from the body whereby said fuselage may be operated independently as a glider or applied 10 upon another body.

The primary object of my invention is to provide an improved aeroplane wherein the fuselage is made separable from the body whereby, in event the propelling means becomes 15 inoperative, the fuselage may be released and operated independently as a glider to facilitate the landing of said fuselage without damaging the same and without injury to the operator or passengers.

Another important object is to provide an 20 improved aeroplane of the character described adapted to permit the fuselage, the planes and rudder and their controls to be released from one body and secured to another body whereby said fuselage may be 25 kept in service during the overhauling of propelling mechanism carried by the first body.

A further object is to provide an 30 improved aeroplane whereby the fuselage and the equipment and contents thereof may be moved from one body to another to avoid the necessity of an entire interchange of aeroplanes for long distance service such as 35 the transporting of mail and the like, thereby effecting a saving in time and avoiding a duplication of equipment.

A still further object is to provide an improved aeroplane embodying improved features of construction adapted to facilitate 40 operation and obtain increased efficiency.

I accomplish these and other objects by means of the improved device disclosed in the drawings forming a part of the present 45 specification wherein like characters of reference are used to designate similar parts throughout said specification and drawings and in which,

Fig. 1 is a side elevation of my improved 50 aeroplane in assembled relation.

Fig. 2 is a side elevation showing the fuselage released from the body.

Fig. 3 is a transverse section of the fuselage and body, the figure being drawn upon 55 a larger scale.

Figs. 4 and 5 are broken sectional details showing the manner in which the securing means carried by the fuselage engage and release respectively the retaining lugs carried by the body. 60

Fig. 6 is a sectional detail showing a plan of a portion of one of the securing members.

Fig. 7 is a broken vertical sectional detail showing the manner in which the instrument board carried by the body is received 65 within the fuselage, and also showing a side elevation of the actuating means for one of the securing members.

Referring to the drawings the numeral 1 is used to designate in general the main 70 body of an aeroplane provided with a propeller 2 actuated from a suitable source of power, not shown, housed within the body 1 in the well known manner. The body is provided with wheels 3 carried upon a suitable framework 4 below the body 1 for landing and for moving the plane upon the ground as in common practice. An instrument board 6 is pivotally mounted upon the body and provided with the usual controls 75 for controlling the propelling mechanism.

A fuselage designated in general by the numeral 7 is arranged to be releasably secured upon the body 1 of the aeroplane. The fuselage 7 consists of a suitable hollow 80 body upon which are secured main planes 8, elevating planes 9, a rudder 10 and suitable control mechanism, not shown, mounted and operating in the well known manner, the plane and rudder controls being carried entirely by the fuselage. The fuselage is provided with seats and storage space arranged 85 to suit the type of machine and the service for which it is designed.

The fuselage 7 is arranged to be secured 90 upon the body 1 by means of securing members 11 preferably consisting of a pair of bars extending longitudinally within the sides of the fuselage and provided with a plurality of wedge shaped extensions 12 arranged 95 to be moved into engagement with apertures 13 formed in lugs 14 carried by the body 1 of the air plane and arranged to extend into the body of the fuselage through openings 16 formed therein. The bars 11 100 are slidably movable within the body of the fuselage and are arranged to be actuated by means of pivotally movable levers 17 positioned within reach of the driver's seat whereby the bars may be moved to cause the 105 110

extensions 12 to engage or disengage the lugs 14 as desired.

The instrument board 6, secured upon the body 1, is arranged to be received within the fuselage 7 through an opening 18 formed therein whereby the controls mounted upon said board may be made visible and accessible to the driver of the aeroplane. The board is made pivotally movable in order to facilitate the placing of the fuselage thereover and to prevent injury to the board or instruments should the fuselage be lowered onto the body the opening 18 is not vertically aligned with the board.

A plurality of leaf springs are secured upon the fuselage 7 and arranged to be compressed and flattened between the fuselage and the adjacent portions of the body 1 when the fuselage is secured in position upon the body 1. The compressed springs 19 tend to separate the fuselage from the body and, while the fuselage remains connected to the body, the springs assist in maintaining a rigid engagement between the extensions 12 and the lugs 14. When the fuselage is released, as hereinafter more fully described, the springs force the fuselage 7 and body 1 apart and insure a quick and positive disengagement. After the fuselage 7 has been released from the body, the springs 19 serve as resilient landing or supporting skids cooperating with a tail skid 21 secured adjacent the rearward end of the fuselage in the ordinary manner, to facilitate landing and to support the fuselage above the ground.

In operation, the fuselage 7, carrying the planes 8 and 9 and the rudder 10 together with the controls therefor, is applied upon the body 1 of the aeroplane by pressing the fuselage downwardly against the pressure of the springs 19 until the lugs 14 enter the corresponding openings 16 in the fuselage. The levers 17 are then operated to move the extensions 12 of the bars 11 into engagement with the apertures 13 in said lugs 14. The wedge shape extensions force the fuselage downwardly into close contact with the body 1 and effectually secure to fuselage in engagement with the body. The levers 17 are preferably locked against inadvertent movement by means of suitable links 22 or other suitable securing means. As thus secured, the fuselage 7 and body 1 combine to form an aeroplane of a form similar to the ordinary aeroplane and operating in a manner fully analogous thereto.

Should the propelling mechanism of the aeroplane become inoperative during the course of the flight, the operator may release the fuselage from the body 1 of the aeroplane by moving the levers 17 to cause the extensions 12 to disengage the lugs 14. When the lugs 14 are disengaged, the springs 19 immediately force the fuselage

and body apart, thus permitting the body to fall to the ground separately from the fuselage. The fuselage now may be independently operated as a glider, the plane and rudder controls remaining intact with the fuselage. When relieved of the excessive weight and resistance of the body and propelling mechanism, the fuselage may be controlled with comparative ease and by manipulating the device as a glider a safe landing may be accomplished without damage to the fuselage and its equipment and without injury to the operator and any passengers accompanying him. Thus in case the engine becomes disabled or inoperative for any reason, the occupants of the machine and a portion of the machine itself may be saved and the loss restricted to the body and propelling mechanism of the machine. In landing the fuselage, the springs 19 operate as resilient landing skids absorbing the shock of impact with the ground and preventing serious damage to the fuselage.

In addition to the value in saving life and property, as above explained, my invention is of particular value and utility in effecting economy where a number of aeroplanes must be kept in constant service. As is well known, the propelling mechanism of an aeroplane is subject to extremely high strain, and must be completely overhauled at frequent intervals. In the ordinary type of aeroplane the entire machine must be taken out of service while such overhauling and repairing is being done. My present invention affords a means for utilizing the fuselage and the equipment carried thereby to be utilized in connection with any of two or more bodies provided with the necessary propelling mechanism. In this way, the main body and propelling mechanism only need be taken out of service for overhauling and repair while the fuselage, planes, rudder and controls, which are not subject to excessive wear and do not require such frequent overhauling, may be applied upon another body and kept in service continuously. This effects a large saving as the duplication of planes, rudders, controls, fuselage bodies and associated mechanisms heretofore necessary may be avoided to a very large extent.

My invention is also of great utility and value in connection with long distance air service such as the transporting of mail and the like wherein it is customary to change planes at certain points along the route. Such changes have heretofore required that the cargo be unloaded from one aeroplane and reloaded upon another plane before setting forth upon each succeeding stage of travel. By my invention, the entire fuselage may be released from one body and moved as a unit onto the body intended for the succeeding stage. The changing of the fuselage from one body to another may be

accomplished in a very brief interval of time and a substantial saving of time effected in making such transfer.

A spring actuated cover 24 may be applied to normally close the opening 18 to exclude water from the body should the fuselage descend upon a body of water. In this manner a landing may be safely made upon the water, the buoyancy of the fuselage 7 serving to keep the same afloat.

While I have illustrated and described what I now consider to be the preferred form and construction of my invention, the device is of course subject to modification in numerous ways without departing from the spirit of my invention. I therefore do not wish to restrict myself to the specific features of construction described, but wish to avail myself of all modifications which may fall within the scope of the appended claims.

Having thus described my invention what I claim as new and desire to secure by Letters Patent is,

1. An aeroplane comprising a body provided with propelling means; a detachable fuselage adapted for independent operation as a glider; and means for normally securing the fuselage to the body and operable for releasing said fuselage from said body.

2. An aeroplane comprising a body; propelling means mounted upon the body; a fuselage; planes and a rudder mounted upon the fuselage; and means for detachably securing the fuselage upon any of a plurality of bodies and released when in flight for independent operation as a glider.

3. An aeroplane comprising a body; propelling means mounted upon the body; a fuselage; planes and a rudder mounted upon the fuselage, said fuselage being adapted to be operated as a glider independently of the body; a plurality of securing elements arranged to normally secure the fuselage upon the body; and means for operating the securing elements to release the fuselage from the body.

4. An aeroplane comprising a body; a propelling means mounted upon the body; a fuselage; planes and a rudder mounted upon the fuselage, said fuselage being adapted to be operated as a glider independently of the body; securing means detachably securing the fuselage upon the body and operable to release said fuselage from said body; and means for moving the fuselage out of engagement with the body when released.

5. An aeroplane comprising a body provided with propelling means; a fuselage releasably secured upon the body and adapted for operation as a glider independently of the body; and resilient means mounted between the fuselage and body for moving the same apart when the fuselage is released from the body.

6. An aeroplane comprising a body pro-

vided with propelling means; a fuselage releasably secured to the body and adapted for operation as a glider independently of the body; and springs normally compressed between the fuselage and the body to force the same apart when said fuselage is released from said body.

7. An aeroplane comprising a body; a fuselage releasably secured to the body and adapted for operation as a glider independently of the body; and a plurality of leaf springs secured to the fuselage and normally compressed between said fuselage and the body to force the same apart when said fuselage is released from said body, said springs being adapted to operate as resilient landing skids for the fuselage when separated from the body.

8. An aeroplane comprising a body; a fuselage adapted for operation as a glider independently of the body; a plurality of retaining members connected to the body and arranged to engage the fuselage; and securing means mounted upon the fuselage and arranged to detachably engage the retaining members for releasably securing the fuselage upon the body whereby the fuselage may be secured upon any of a plurality of bodies or released from a body when in flight.

9. An aeroplane comprising a body; a fuselage adapted for operation as a glider independently of the body; a plurality of retaining members connected to the body and arranged to engage openings formed in the fuselage; and securing means mounted upon the fuselage and movable into detachable engagement with the inwardly extending portions of the retaining members for releasably securing the fuselage upon the body whereby the fuselage may be secured upon any of a plurality of bodies or released from a body when in flight.

10. An aeroplane comprising a body; a fuselage adapted for operation as a glider independently of the body; a plurality of lugs formed upon the body and arranged to engage openings formed in the fuselage; and securing elements slidably movable into engagement with the lugs to releasably secure the fuselage upon the body whereby the fuselage may be secured upon any of a plurality of bodies or released from a body when in flight.

11. An aeroplane comprising a body; a fuselage adapted for operation as a glider independently of the body; a plurality of lugs formed upon the body and arranged to engage openings formed in the fuselage; and securing elements slidably movable into engagement with the lugs to releasably secure the fuselage upon the body whereby the fuselage may be secured upon any of a plurality of bodies or released from a body when in flight; and means for moving the

- body and fuselage apart when said fuselage is released.
12. An aeroplane comprising a body; a fuselage adapted for operation as a glider independently of the body; a plurality of apertured lugs formed upon the body and arranged to engage openings formed in the fuselage; a pair of bars slidably mounted within the fuselage and provided with extensions arranged to engage the apertures in the lugs; and means for moving the bars to cause the extensions to engage or disengage the lugs whereby the fuselage may be releasably secured upon any plurality of bodies or released from a body when in flight.
13. An aeroplane comprising a body; a fuselage adapted for operation as a glider independently of the body; a plurality of apertured lugs formed upon the body and arranged to engage openings formed in the fuselage; a pair of bars slidably mounted within the fuselage and provided with extensions arranged to engage the apertures in the lugs; and means for moving the bars to cause the extensions to engage or disengage the lugs whereby the fuselage may be releasably secured upon any plurality of bodies or released from a body when in flight; and means for moving the body and fuselage apart when said fuselage is released.
14. An aeroplane comprising a body; a fuselage adapted for operation as a glider independently of the body; a plurality of apertured lugs formed upon the body and arranged to engage openings formed in the fuselage; a pair of bars slidably mounted within the fuselage and provided with extensions arranged to engage the apertures in the lugs; and means for moving the bars to cause the extensions to engage or disengage the lugs whereby the fuselage may be releasably secured upon any of a plurality of bodies or released from a body while in flight; and leaf springs arranged to be compressed between the fuselage and body to move the same apart when the fuselage is released.
15. An aeroplane comprising a body; propelling means mounted upon the body; a fuselage; planes and a rudder mounted upon the fuselage; controlling means for said planes and rudder; an instrument board mounted upon the body and arranged to receive controls for the propelling means, said board being arranged to be received within the fuselage through an opening formed therein; and means for detachably securing the fuselage upon the body whereby the fuselage may be released from said body for independent operation as a glider or for attachment upon another body.
16. An aeroplane comprising a body; propelling means mounted upon the body; a fuselage; planes and a rudder mounted upon the fuselage; controlling means for said planes and rudder; an instrument board mounted upon the body and arranged to receive controls for the propelling means, said board being arranged to be received within the fuselage through an opening formed therein; and means for detachably securing the fuselage upon the body whereby the fuselage may be released from said body for independent operation as a glider or for attachment upon another body; and means for moving the fuselage and body apart when said fuselage is released.
17. An aeroplane comprising a body; propelling means mounted upon the body; a fuselage; planes and a rudder mounted upon the fuselage; controlling means for said planes and rudder; an instrument board mounted upon the body and arranged to receive controls for the propelling means, said board being arranged to be received within the fuselage through an opening formed therein; and means for detachably securing the fuselage upon the body whereby the fuselage may be released from said body for independent operation as a glider or for attachment upon another body; and leaf springs arranged to be compressed between the fuselage and body to move the same apart when the fuselage is released, said springs being adapted to operate as landing skids for the fuselage when separated from the body.
18. In an aeroplane, the combination with a body equipped with propelling mechanism, of a fuselage arranged to carry an operator and passengers or freight, said fuselage being detachably secured to the body whereby said fuselage may be applied upon any of a plurality of bodies and whereby said fuselage may be released when in flight for independent operation as a glider.

In witness whereof I hereunto set my signature.

JOAQUIN S. ABREU.
